UNITED STATES PATENT OFFICE.

WERNER EBELL, OF NEURUPPIN, GERMANY.

WARP-TENSIONING DEVICE FOR LOOMS.

Application filed August 30, 1922. Serial No. 585,231.

To all whom it may concern:

Be it known that I, WERNER EBELL, a citizen of the German Republic, residing at Neuruppin, Germany, have invented certain new and useful Improvements in Warp-Tensioning Devices for Looms (for which I have filed an application for patent in Germany on the 12th of May, 1921), of which the following is a specification.

10 This invention relates to a warp tensioning device for looms designed for the weaving of coarse fabric, for instance transmission belts, conveyor bands or the like. The coarse threaded warps used for this purpose are conducted, without prejudicing their strength, between roughened cylinders which are controlled by the pressure of a lever variably loaded by a weight.

15 If the tension of the coarse threaded warps produced by the roughened cylinders should not be sufficient, the warp threads before getting to the point where they are to be used could, in order to increase their tension, be conducted further in a manner known per se around one or several cylinders adapted to be locked.

20 An embodiment of the invention is shown by way of example in the only figure of the accompanying drawing.

25 In the frame *a* of the loom two roughened, rotatably supported cylinders *b* and *c* are arranged one above the other, of which one, the upper cylinder *b*, is non-adjustable, the other, cylinder *c*, being adjustably mounted in slots *d*. Cylinder *c* is controlled by the pressure of a lever *f*, fulcrumed at *e*, which has at its free end a pin *g* upon which weight plates *h* are placed. The lever *f* holds the adjustable cylinder *c* toward the cylinder *b* with a force proportioned to the weight supported upon its outer end. The adjustable cylinder *c* is so mounted that when free from the action of the weighted lever *f* it will automatically fall away from the cylinder *b*, thus leaving sufficient space between these cylinders to pass the warp threads between them as is required when the threads, or some of them, become broken.

30 The warp threads *i* pass between the roughened cylinders *b* and *c* to be conducted over the rollers *k* and *l* to the corresponding shafts of the loom.

35 By varying the load produced by the weight plates *h* the pressure between the cylinders *c* and *b* can be increased or reduced whereby the tension of the warp threads can be regulated.

40 If a warp thread should break the outer end of the weighted lever *f* may be lifted thus freeing the adjustable cylinder *c* from the action of the lever, which thereupon falls away from the cylinder *b* leaving space between the cylinders to pass the broken threads without interfering with the adjustments of any of the permanently mounted or supported parts of the machine. The wearisome work which in such cases becomes necessary with the usual tensioning devices is avoided by the improved tensioning device whereby the efficiency of the loom is considerably increased.

I claim:—

45 An improved warp tensioning device for looms designed for the weaving of coarse fabrics, including, in combination, a pair of rotatably supported cylinders arranged one above the other, between which are passed the warp threads, the upper cylinder being non-adjustable and the lower one being mounted so as to freely move away from the non-adjustable cylinder when unsupported, a lever acting upon the lower, adjustable, cylinder to hold it toward the upper cylinder with yielding pressure, and weights carried at the outer end of the lever so that variable pressure may be exerted upon the adjustable cylinder, the lever being arranged so that when its outer end is lifted the adjustable cylinder is freed and allowed to move away from the non-adjustable cylinder.

50 In testimony whereof I affix my signature.

WERNER EBELL.
